DESIGN FOR A CHAIN

Christian F. Kohm, Cranston, R. I., assignor to
Speidel Corporation, Providence, R. I., a cor-
poration of Rhode Island

Application March 1, 1934, Serial No. 50,910

Term of patent 7 years

To all whom it may concern:

Be it known that I, CHRISTIAN F. KOHM, a citizen of the German Republic, residing at Cranston, in the county of Providence and State of Rhode Island, have invented a new, original, and ornamental Design for a Chain of which the following is a specification, reference being had to the accompanying drawing, forming part thereof.

Fig. 1 is a side elevational view of a section of the chain made up of a plurality of links, and,

Fig. 2 is a top plan view of one of the chain links.

What I claim is:—

The ornamental design for a chain, substantially as shown.

In testimony whereof I have affixed my signature.

CHRISTIAN F. KOHM,
